UNITED STATES PATENT OFFICE.

JOHN P. DELPHEY, OF TOLEDO, OHIO.

WIRE-PAY-OUT REEL.

SPECIFICATION forming part of Letters Patent No. 732,835, dated July 7, 1903.

Application filed April 23, 1902. Serial No. 104,345. (No model.)

To all whom it may concern:

Be it known that I, JOHN P. DELPHEY, a citizen of the United States, and a resident of the city of Toledo, in the county of Lucas and 5 State of Ohio, have invented certain new and useful Improvements in Wire-Pay-Out Reels, of which the following is a description.

The object of this invention is to, first, provide a strong, durable, inexpensive light band 10 or hoop for wire-pay-out reels that will not easily break, that will also act as a brace to the reel-arms, and which also may be used as a handle to lift the reel and carry it about; second, provide a simple, strong, inexpensive 15 combination of parts by way of fastening the band or hoop to the arms of a pay-out reel; third, provide a simple, convenient, and effective combination of parts by way of fastening and adjusting the uprights to the reel- 20 arms; fourth, provide a combination of parts and material in a wire-pay-out reel light, inexpensive in construction, more convenient, more durable, and more satisfactory in its 25 working than any other plain band pay-out reel of its class.

With these and other objects in view the invention consists of certain new and novel features of construction, combination, and arrangements of parts, which will hereinafter 30 be more fully described, and particularly pointed out in the appended claims.

Figure 1 is a complete wire-pay-out reel in perspective with all the improvements. Fig. 2 is a perspective of the outer end of a reel-arm, showing a broken-off portion of the band or hoop and a manner of connecting the same with the reel-arm band. The band is here shown as tubular. Fig. 3 is an elevation of the reel-hub and pivot parts to which the 35 arms and legs are attached at the concave parts, two of which concavities are shown in the foreground. Fig. 4 is an elevation in section of the pivot parts and reel-hub with broken-off arms and legs, showing the manner 40 of attaching the arms and legs to the hub and pivot castings with the form of the pivot and hub and their immediate connections.

Similar letters refer to similar parts throughout the several views in the accompanying 45 drawings.

A A is the hub or swivel or central revolving portion of the reel and bears the arms B B B and each arm B an adjustable upright

b thereon and revolves about the pivot C and rests on the shoulder D at the lower part of 55 the pivot C.

E is the base of the reel-pivot, and each F is a leg supporting the reel, and each fits into its corresponding cavity similar to the one in front at V and at or about at right angles to 60 the pivot-axis and set squarely against the metal at the inner end of the concavity at U, being thus held firmly in place by the attaching bolts or rivets acting straight. The legs and arms are attached to their respective parts of the reel parts A and E by means of rivets or bolts, each of which is represented by c through the corresponding holes r r' in the arms and legs, respectively, being two or more holes and bolts or rivets through each 65 casting-arm of the central reel parts for the attached metal arm or leg, thereby holding the same together rigidly and not liable to get out of order. To the base E of the reel-pivot and about the reel-pivot C is held the 70 reel-hub A by the nut N and washer L on the extension of the reel-pivot.

T is an adjustable T-piece with set-screws s and s₁ in each of its branches, the one, s, at the upper part of the arm being in the angle 80 of the T and toward the center of the reel, the other, s₁, being at or near the other extremity of the T and away from the wire about the outside of its corresponding upright b to give the operator as much room as 85 possible consistent with light, weight, and space. The set-screw s holds the upright b corresponding therewith in place to or from the wire surrounding its outer side when in use, and the set-screw s₁ regulates the position 90 of the T and the upright on the reel-arm when and where either is adjusted to suit the operator. It can be tightened and the whole held in any position desired, and the set-screws s and s₁ are out of the way of the wire 95 on the reel-arms about the uprights.

X is the reel-band, oval, tubular, rectangular, or angular, having a thickness nearly equal or equal to its width, so welded, brazed, or otherwise united together at the ends of 100 the piece from which formed as to form a surface even and smooth in conformation with the adjacent parts of the band and fastened to the outer part of the reel-arm B at B, where is also the concavity in the reel 105 band or hoop at its junction with the reel-

arm B that the thickness of the band may not raise it too high above the surface of the reel-arm B and interfere with the wire paying out when the reel is in use.

5 $r'' r''' r_{111}$ are the holes through the band and reel-arm, respectively, through which are fastened the bolts or rivets which hold the parts together, the hole in the band at r'' being countersunk, as indicated, to permit of a 10 bolt or rivet being used with head converging from the body of the bolt or rivet and fitting into the countersunk hole and permitting of a straight flat surface on the top of the reel band or hoop. $w w$ at the ends of the 15 broken-off arms show that tubing is here indicated.

From the foregoing description, taken in connection with the accompanying drawings, the construction, mode of operation, and advantages of the invention will be understood readily without requiring more extended explanation.

In practice I prefer to use two-hole arm-castings, round metal tubing for arms, legs, 25 uprights, and bands attached to the central parts, where so attached by flat-head stove-bolts and lock-nuts, and the band riveted to the outward part of the reel-arms, as indicated, though it is obvious that metal of various forms of section may be used for arms, 30 legs, uprights, and bands and arms and legs fastened to the pivot-arms by various kinds of bolts and rivets and the band flattened at the point of junction with the reel-arm, as indicated in the drawings; but the arm alone 35 may be flattened or hollowed out to conform to the shape of the band or both may be made partially to conform to the other and all of which I claim as part of this invention, and 40 also other obvious changes can be made in the various mechanical devices in form, proportion, and details of construction which will be within the scope of the invention without departing from its spirit or sacrificing 45 the advantages thereof in any respect.

Having thus described my invention, what I claim and desire to secure by Letters Patent, is—

1. The combination in a wire-pay-out reel 50 of a cone-shaped pivot, with a corresponding cone-shaped hub, with legs and arms radiating therefrom, a metal band on the outer portion of the reel-arms, and uprights or fingers to hold the wire on the reel.

55 2. In a wire-pay-out reel, a band or hoop upon the outer portion of the reel-arms, with the section of the band equal or nearly equal its width and flattened at its under side or otherwise shaped in conformity to the shape 60 of the upper side of the reel-arm at such point of contact so as to permit of being readily fastened to the reel-arms, but permitting the top of the band to be perfectly smooth in line and little, if any, elevated above the surface 65 of the reel-arms.

3. In a wire-pay-out reel, a band or hoop with section equal or nearly equal its width

upon the outer portion of the reel-arms, with the reel-arms shaped at their point of contact with the reel-band in conformity thereto so as 70 to permit of the band and arm being readily fastened at such point of contact, but permitting the band to be perfectly smooth in line and little, if any, elevated above the surface of the reel-arms. 75

4. In a wire-pay-out reel, a band or hoop upon the outer portion of the reel-arms, with the reel-arms and band so flattened and shaped at their point of contact as to permit the band and arm to be readily fastened at their 80 point of contact, but permitting the band to be perfectly smooth in line and little, if any, elevated above the surface of the reel-arms.

5. In a metal wire-pay-out reel, a metal band or hoop upon the outer portion of the 85 reel-arms, and the band or hoop and the reel-arms fastened together by means of a bolt or rivet through the band and the outer extremity of the arm, through holes therein and countersunk on the upper side of the reel- 90 band permitting a converging shoulder or head of the bolt or rivet to be held therein and the band to be smooth in line on its upper surface.

6. The combination in a wire-pay-out metal 95 reel of a metal band, upon the outer portion of the reel-arms, adjustable uprights attached and held by set-screws to adjustable T's, and they similarly adjustable and held in place on the reel-arms by set-screws, a 100 cone-bearing hub having metal arms attached thereto by two or more nuts or bolts each, a cone-bearing and cone-shaped pivot with somewhat-elliptically-shaped metal legs, and legs attached to the reel-pivot casting by two 105 or more rivets or bolts each.

7. The combination in a wire-pay-out reel of a metal band upon the outer portion of the reel-arms, adjustable uprights attached and held to adjustable T's, and they adjustable 110 and held in place on the reel-arms, a cone-bearing hub having metal arms radiating therefrom and a cone-shaped pivot having metal legs radiating therefrom.

8. The combination in a wire-pay-out reel 115 of a metal band upon the outer portion of the reel-arms, uprights which may be adjusted to any desired place along the arm, and a metal hub and pivot with arms and legs radiating therefrom. 120

9. The combination in a wire-pay-out reel of a metal band upon the outer portion of the reel-arms, uprights held in place and adjustable on and along the reel-arms, and a metal cone-shaped pivot with corresponding cone-shaped hub, with legs and arms radiating therefrom. 125

In testimony whereof I have hereunto signed my name to this specification in the presence of two subscribing witnesses.

JOHN P. DELPHEY.
